UNITED STATES PATENT OFFICE.

HIRAM PERCY MAXIM, OF HARTFORD, CONNECTICUT.

DESIGN FOR A PLUG FOR ELECTRICAL PURPOSES.

SPECIFICATION forming part of Design No. 28,744, dated May 31, 1898.

Application filed April 9, 1898. Serial No. 677,096. Term of patent 14 years.

To all whom it may concern:

Be it known that I, HIRAM PERCY MAXIM, a citizen of the United States, and a resident of the city and county of Hartford, State of Connecticut, have invented a certain new and original Design for a Plug for Electrical Purposes, of which the following is a specification, reference being had to the accompanying drawings, forming a part hereof.

- o This invention relates to plugs such as are employed for the purpose of making connection between an electrical supply-cable and a storage battery or other like purposes; and it consists in the form and configuration of the

5 design, as hereinafter more particularly described.

In the drawings, Figure 1 is a view in side elevation of a plug formed in accordance with my invention. Fig. 2 is an elevation of the

- o same as seen from the right in Fig. 1.

A plug which embodies my design may be described in general terms as for or Y shaped, having three members A, A', and A². Each member A' and A² has near its extremity a

tapering portion a, which runs into a portion 25 a' of reduced diameter. Between each portion a' and the member A is a portion a², substantially at right angles with the axis of the portion a' and of the member A, the two portions a² running into each other and having 30 the member A disposed at the point of junction of the two at substantially right angles therewith or parallel with the axes of the portions a a'. The member A is substantially circular in cross-section and when viewed in 35 side elevation is seen to be of reduced diameter between its outer end and its point of junction with the members A' A².

I claim as my invention—

The design for a plug for electrical purposes, substantially as shown and described.

This specification signed and witnessed this 22d day of May, A. D. 1897.

HIRAM PERCY MAXIM.

In presence of—

FELTON PARKER,
HERMAN F. CUNTZ.
